The present invention refers to a transfer circuit system for transferring step-by-step information along a chain consisting of a plurality of stages in response of stepping forward impulses fed to said chain.

It is known to use in counters, pulse distributors, shift-registers and the like, electron tube- or transistor-relaxation circuits, glow discharge tubes or bistable magnetic circuits connected in a chain in order to provide such a step-by-step transfer of information. All such chains include in their stages a network which stores energy with a certain time constant and allows transfer of the information from one stage to another when said stepping forward impulse occurs. A typical chain of this type comprises a chain of glow discharge tubes in which capacitors are used to make certain that the tube fired at the beginning of the forward stepping is extinguished and the following tube and no other tube will be fired. It is however difficult to construct chains of said type comprising more than about ten elements owing to the disturbing potentials obtained from the preceding and following stages and owing to the fact that the time constants of the energy accumulating circuits of the stages of the row are normally varying within broad limits from stage to stage. Furthermore well defined rectangular output pulses are generally required and such a shape is difficult to obtain from chains of said type. Furthermore it may be difficult in certain cases to obtain a sufficient separation between two successive pulses. A further drawback which in certain cases can be of importance, is that the chain in the known devices will be set to "zero-condition" when the current supply is momentarily interrupted. Certain magnetic chains comprising magnetic cores which have a rectangular hysteresis loop, have the further drawback that disturbing pulses obtained when a remagnetizing pulse is applied to a core already remagnetized, may be superposed and cause erroneous stepping.

All said drawbacks are eliminated in a chain according to the present invention. Said chain produces output pulses of satisfactory shape and relatively good effect and the consumption of the chain between the stepping impulses is negligible. The chain can furthermore retain the last occupied position for an unlimited time even if the current supply is interrupted, and the chain will resume the same stepping sequence it had before the interruption of current. Owing to the fact that the chain does not comprise any energy accumulating element having a time constant which can vary from stage to stage, very well defined output pulses are obtained.

A transfer circuit arrangement according to the invention for step-by-step transmitting information along a chain consisting of a plurality of stages, in response of stepping impulses fed to the chain, comprises in each stage of the chain bistable relaxation circuits having an input for setting said circuit to working position and another input for restoring the relaxation circuit to rest position and a magnetic core having a substantially rectangular hysteresis loop and provided with three windings, a first one of said windings being connected to the output of said bistable relaxation circuit in such manner that it is passed by a current magnetizing the core to a first remanence condition when said relaxation circuit is in working position, a second winding being connected to a stepping impulse

source tending to set the core to another remanence condition, a third winding being connected to the input for switching the relaxation circuit of the following stage in such manner that a switching impulse is obtained as soon as the magnetic condition of the core is changed from the first to the second remanence condition. The stepping impulse source produces in response to each stepping two impulses separated in time, one of which impulses is applied to said second winding on each core and the other one is applied to the input for restoring all the relaxation circuits.

An embodiment of the invention will be explained in the following with reference to the enclosed drawing.

The chain shown in the figure comprises for sake of simplicity only three stages I, II and III but it can comprise a very great number of stages. Chains having twenty stages have been tested and been found to work extremely well with safe stepping. The different stages of the chains are identical, except for a starting winding in the first stage. Each stage comprises a transistor-relaxation circuit having a pnp-transistor T1 and a non-transistor T2 which are fed back in such a way that either both are closed thereby defining the off or non-conduction state of the relaxation circuit or both are conducting thereby defining the on or conduction state of the relaxation circuit (Hook-chain), and a magnetic core M1, M2 and M3 respectively having a rectangular hysteresis loop. Each core is provided with three windings 1-2, 3-4 and 5-6 which are arranged and connected in such a way that the winding 1-2 causes a flux in the core having opposite direction relative to the flux caused by the windings 3-4 and 5-6. On the core M1, there is furthermore situated a starting winding 7-8, which is wound and connected in such a way that it tends to magnetize the core in the same direction as the winding 1-2. The inclined lines across the cores in the figures indicate the magnetizing direction caused by the respective winding in the shown circuit, a line inclined in the right-hand direction (3-4 and 5-6) indicating that the winding will magnetize the core to a remanence condition which in the following will be called zero-position while a line inclined in the left-hand direction indicates that the core is magnetized to opposite remanence conditions, in the following called one-position.

The stepping of the chain is carried out by means of an impulse source producing two relatively phase-displaced impulses at two different outputs w1 and w2. At first a stepping impulse occurs at the input w1 affecting a relaxation circuit and said stepping impulse is always followed by a restoring impulse which restores the relaxation circuit to rest position. For sake of simplicity in the figure the impulse source has been indicated as two contacts K1 and K2 which are successively closed for a short period of time. A contact K3 is used for connecting the starting winding 7-8 on the core M1 to a magnetizing current source. The circuit arrangement is fed by a current source having a grounded terminal (0), a relatively positive terminal (plus) and three negative terminals (E1, E2 and E3) where E1 is least negative and E3 is most negative.

Each relaxation circuit of the above mentioned type comprises a pnp- and a npn-transistor. The base of the pnp-transistor T1 is connected through the base impedance r2, C1 to the collector of the npn-transistor T2, while the base of the npn-transistor T2 is connected through the base impedance r5, C2 to the collector of the pnp-transistor T1. The emitter of the transistor T1 is grounded and the collector, in addition to being connected to the base of the transistor T2, is connected to impulse output U1 and to the terminal E1 of the potential source through the resistance r4. The base of the transistor T1 is connected through the resistance r1 to the input for restoring impulses, common for all the stages. The emit-

ter of the transistor T2 is connected to the terminal E1, and the collector, in addition to being connected to the base circuit of the transistor T1, is connected to ground through the resistance r3. The base of the transistor T2 is connected to the terminal E3 through the resistance r6 and to the terminal E2 through the diode d1 and the winding 3-4 on the next preceding core of the row. The cathode of the diode is connected to the base of T2.

While non-conducting the transistor T2 is blocked owing to the base being maintained at the potential E2 which is negative relatively to the emitter, by means of the conducting diode d1. In the same manner the base of the transistor T1 obtains a bias positive relatively to the emitter, through the resistance r7 so that the transistor is securely blocked. If the base of the transistor T2 obtains a positive impulse, this transistor will become conducting and takes collector current from ground through the resistance r3 and the winding 1-2 on the respective core. The base potential of the transistor T1 will then decrease to such a degree that this transistor will also become conducting. The collector current of T1 causes a potential drop along the resistance r4 increasing the base potential of the transistor T2 to such an extent that the latter will be maintained in a conducting state after the controlling impulse ceases. The relaxation circuit is restored by a positive impulse being applied to the base of the transistor T1 which will be choked, causing that the transistor T2 will be also choked.

Transistor relaxation circuits of the type described have the advantage in comparison with other bistable relaxation circuits that the current consumption is negligible in rest position. The chain is consequently built in such a way that the relaxation circuits normally are in off or non-conduction state, except upon stepping when a relaxation circuit is made conducting. The time for which said relaxation circuit should be conducting is defined by the required duration of the impulse occurring on the terminal U1. Said duration can be varied by varying the length of the period between the stepping forward- and restoring impulses as desired within the whole time period between two succeeding stepping impulses. The memory function required in order to recognize the adjustment of the chain between the stepping impulses is obtained by means of the cores M1-M3.

The device functions as follows:

Let it be assumed that all the cores are from the beginning magnetized to zero-position and that all the relaxation circuits are in the non-conduction state. The chain is prepared for stepping by magnetizing the core to one-position by closing a circuit momentarily from plus potential through the winding 7-8 to ground. When a stepping impulse is applied to the series connected windings 5-6 in the different stages by momentarily connecting them between plus potential and ground through the contact K1, only the core M1 will be remagnetized to zero-position as the other cores have already said position. Upon remagnetizing, a positive impulse is induced in the winding 3-4 which impulse will be applied to the base of the transistor T2 in the relaxation circuit of stage II through the diode d1 thereby rendering the transistor T2 and consequently also the transistor T1 conducting. The transistor T2 obtains its substantial collector current through the resistance r3 and the winding 1-2 on the core M2 for which reason the latter is magnetized to one-position. As mentioned before, each stepping impulse on the input w1 is followed by a restoring impulse on the input w2 which is obtained by momentarily connecting the contact K2 to plus potential. The base potential of the transistor T1 will be increased in such a degree that the transistor will be choked. Upon ceasing of the collector current, the potential of the base of the transistor T2 will decrease and this transistor will be also choked. None of the relaxation circuits is conducting before the next stepping impulse is obtained for which reason the consumption in rest position is negligible. When the next stepping impulse is obtained, the stepping

process will be repeated in exactly the same way as described hereabove, the core M2 being restored to zero-position and the relaxation circuits of the stage III will produce an impulse magnetizing core M3 to one-position.

5 The chain shown in the figure is intended to be used as impulse distributor for which reason the different stages are ring connected, that is, the winding 3-4 on the core M3 is connected to the stepping input of the relaxation circuit of stage I. The different, relatively displaced pulse series are obtained from the outputs U1.

10 As only one core is magnetized to one-position or zero-position respectively at the same time, the counter-electromotive force obtained upon remagnetizing is always the same, that is, the sum of the counter-electromotive force obtained from the remagnetized core plus the small disturbing potentials obtained from the cores which will not be remagnetized. Thus it is possible to have relatively long chains driven from the same source of stepping impulses. Experiments have shown that it is possible with a working potential of about six volts to drive more than twenty cores in series and to obtain a secure stepping. If still longer chains are required they can be divided into a number of groups. In each group the windings 5-6 are connected in series and said groups of series-connected windings are driven parallel for decreasing the influence of the disturbing potentials. Each group may have its own stepping impulse source, all said driving impulse sources being of course synchronized.

15 By applying to all the cores an impulse for restoring zero-position respectively at the same time, the counter-electromotive force obtained upon remagnetizing is always the same, that is, the sum of the counter-electromotive force obtained from the remagnetized core plus the small disturbing potentials obtained from the cores which will not be remagnetized. Thus it is possible to have relatively long chains driven from the same source of stepping impulses. Experiments have shown that it is possible with a working potential of about six volts to drive more than twenty cores in series and to obtain a secure stepping. If still longer chains are required they can be divided into a number of groups. In each group the windings 5-6 are connected in series and said groups of series-connected windings are driven parallel for decreasing the influence of the disturbing potentials. Each group may have its own stepping impulse source, all said driving impulse sources being of course synchronized.

to set said sequential relaxation circuit to its conduction state, and circuit means connected to the second input of the relaxation circuits in said chain to feed reset pulse to the relaxation circuits in all the stages to set said circuits to the non-conduction state.

2. A circuit arrangement according to claim 1 in which each of said relaxation circuits comprises a npn-transistor and a pnp-transistor, the base of each transistor being connected to the collector of the other transistor in the respective circuit whereby either both transistors are blocked to set the respective relaxation circuit in the non-conduction state or both transistors are conducting to set the respective relaxation circuit in the conduction state.

3. A circuit arrangement according to claim 1 in which at least one of said stages comprises a means for setting said one stage to a state in which it is sensitive to the pulses fed to said stage.

4. A circuit arrangement according to claim 3, in which said means for setting said one stage comprises an additional winding on the core for magnetizing the core to its first remanence condition by connecting said additional winding to a current source.
